UNITED STATES PATENT OFFICE.

THEODORE W. FOSTER, OF PROVIDENCE, RHODE ISLAND.

DESIGN FOR A JEWELRY-PIN.

SPECIFICATION forming part of Design No. 15,050, dated June 10, 1884.

Application filed March 17, 1884. Term of patent 7 years.

To all whom it may concern:

Be it known that I, THEODORE W. FOSTER, of Providence, in the State of Rhode Island, have invented and produced a new and original Design for the Plate of a Jewelry-Pin, of which the following is a specification, reference being had to the accompanying drawings, forming a part thereof.

Figure 1 is an edge view of my newly-designed front plate of a jewelry-pin. Fig. 2 is a sectional view of the same. Fig. 3 is a face view, and Fig. 4 a section taken in the line $x x$ of Fig. 3, these four views being deemed necessary to fully illustrate my design.

The leading features of my design consist in a plate the outline and front surface of which is made to represent a table-fork, with the continuous outline edge of the plate turned backward for a nearly uniform distance from its front, and also having an engraved, chased, or embossed handle.

In the accompanying drawings, A is the plate, having the form of a table-fork, the handle a , and tines b of which are provided with a nearly uniform backwardly-turned edge, c , and the handle a is also provided with the engraved, chased, or embossed ornamentation d ; but the form and style of the ornamentation d may be varied without affecting the general appearance of the whole design.

I claim as my invention—

The design for a jewelry-pin herein shown and described, the same consisting of a plate having the shape of a table-fork, with the outline edge of the plate turned backward at a nearly uniform distance from its front, and the surface of the handle of the fork showing an embossed or engraved ornamentation.

THEODORE W. FOSTER.
